FIG. 4.

Inventor

H. G. Gillmor

UNITED STATES PATENT OFFICE.

HORATIO G. GILLMOR, OF PORTSMOUTH, VIRGINIA.

RAIL-ANCHOR.

1,107,782.

Specification of Letters Patent. Patented Aug. 18, 1914.

Application filed May 12, 1913. Serial No. 767,129.

To all whom it may concern:

Be it known that I, HORATIO G. GILLMOR, of Portsmouth, in the county of Norfolk, State of Virginia, have invented a new and useful Improvement in Rail-Anchors, of which the following is a specification, accompanied by drawings.

This invention relates to a device known as rail anchors, or anti-creepers, and one of its objects is to form a simple device which will prevent longitudinal movement of the rails of railways.

Another object of the invention is to provide means of automatically tightening the grip of the anchor upon the rail.

To the accomplishment of these objects and such others as may hereinafter appear, as will be readily understood by those skilled in the art, the invention comprises a rail anchor—embodying features of construction the combination of elements and arrangement of parts having the general mode of operation as hereinafter described and claimed.

The preferred embodiment of the invention is shown in the accompanying drawings, in which:—

Figures 1 and 2 are, respectively, a sectional view and a side elevation of the rail anchor. Fig. 3 is an end view of the device, showing the position of the dog when being forced into place. Fig. 4 is a plan view of the bottom of the clamp.

Similar letters apply to similar parts throughout the several views.

In the embodiment of the invention illustrated in the drawings "A" is the rail, "B" is a clamp constructed to accurately fit the bottom of the rail and engage with the flange at the side of the rail. "C" is a dog; "D" is a tie or sleeper. The clamp "B" is constructed with a face "E," arranged in any convenient position below the rail to bear upon the side of the tie "D," and a rib or web "F," which is notched at "G" to receive the dog. The surface of this notched portion "G" of the web "F" which will engage with the dog "C" is preferably cylindrical. The clamp "B" is also provided with a jaw "H" to engage with the flange of the rail at one side. The dog "C" is constructed with a hook portion "I" to engage with the notch "G" in the web "F" and the engaging surfaces "K" of the dog "C" and the clamp "B" are preferably

cylindrical. An arm "L" of the dog engages with the upper surface of the flange of the rail on the side opposite to the clamp jaw. The dog "C" is provided with a projection "M" which may conveniently be struck with a hammer to remove the dog.

The device is placed in position by placing the clamp "B" with the face "E" against the tie and the jaw "H" engaging with the flange of the rail. A light blow with a hammer will set the clamp upon the rail. The dog "C" is then placed with the hook portion "I" engaging the notch "G" in the web "F," and the arm "L" engaging with the edge of the flange of the rail opposite to the clamp jaw "H." The dog is then driven into place by blows with a hammer, or in some other suitable manner, and the clamp "B" is in this way drawn into contact with the under surface of the base of the rail and at the same time subjected to a transverse pull causing the jaw "H" to grip firmly the flange of the rail.

The direction in which the rail tends to move is indicated by the arrow in Fig. 2. The pressure between the surfaces of the clamp "B" and the rail "A" when the dog "C" is finally in position will generally effectually prevent any movement of the rail "A" upon the tie "D," but should slight movement occur the dog "C," which is rotatably held at its lower end "I" on the clamp "B" and has its arm "L" engaging with the rail flange will move forward with the rail and assume the position indicated by the dotted lines in Fig. 2. This action will automatically increase the pressure between the clamp and the rail and the anchor is therefore automatically tightened and further movement prevented.

Obviously some features of the invention may be used without others and the invention may be embodied in widely varying forms within the scope of the artisan.

Therefore, without limiting the invention to the construction shown and described or enumerating equivalents, I claim and desire to secure by Letters Patent—

1. A clamp constructed with an upwardly and inwardly overturned portion at one end forming a jaw adapted to engage with a rail flange and at the other end thereof a downwardly projecting portion constructed so to engage with a vertical pressure producing part as to permit rotational movement

of said vertical pressure producing part in relation to said clamp.

2. A rail gripping part constructed with a rail base flange engaging portion at one end, a transversely extending portion provided with a depending tie engaging portion and, at the other end a downwardly projecting portion provided with a recessed seat adapted to pivotal engagement with a vertical pressure producing part.

3. A vertical pressure producing part for rail anchors constructed so to engage a rail bottom engaging part below the rail that rotational movements of said pressure producing part about an axis below the rail will force surfaces of said pressure producing part into engagement with the upper surface of the base flange of the rail and thereby produce pressure of the bottom engaging part upon the bottom of the rail, substantially as described.

4. A part for anti-creepers constructed with an arm adapted to engage a rail above the base thereof and a hook adapted so to engage a rail bottom engaging element below the rail as to permit angular movements of said part about axes at right angles the one to the other.

5. An anticreeper for rails comprising a rail gripping element and a part engaging the upper surface of the rail base at the side of the rail opposite to said gripping element and so pivoted to said gripping element as to be rotatable about a longitudinal axis below the rail and between the edges thereof for effecting the gripping action of said element.

6. A rail anchor, including in combination with the rail, a flange gripping and bottom engaging part and a vertical pressure producing part adapted so to engage with the rail above and said bottom engaging part below the rail base that movement of the rail in relation to said flange gripping and bottom engaging part will produce rotational movement of said vertical pressure producing part and thereby increase the pressure of said parts upon the rail.

7. In a rail anchor, the combination of a flange embracing and gripping and bottom engaging part, constructed with a tie abutting portion, and a vertical pressure producing part, constructed to engage with the rail above and said bottom engaging part below the rail foot flange, so arranged that longitudinal movement of said bottom engaging part in relation to said rail will produce angular movement of said vertical pressure producing part about a transverse axis and automatically increase the gripping action of the device upon the rail.

8. A rail anchor comprising a transversely extending part engaging with the top and edge of the rail foot flange at one side of the rail and with the bottom of the

rail at the other side of the rail and a vertically extending part constructed to engage with the top of the rail foot flange at the side opposite to that engaged by said transversely extending part and to have pivotal engagement with the transversely extending part below the rail.

9. In a rail anchor, the combination of a transversely extending part engaging with the side of the rail foot flange at one side and constructed with a downwardly projecting portion at the opposite side of the rail and a vertically extending part so engaging with the downwardly extending portion of the transversely extending part below and the upper surface of the rail above the rail foot flange that rotation of said vertically extending part about said transversely extending part in a transverse plane will cause said transversely extending part to grip the side and bottom of the rail and that longitudinal movement of the rail in relation to said transversely extending part will produce angular movement of said vertically extending part and automatically increase the grip of the parts upon the rail.

10. A rail anchor, including, in combination with the rail, a transversely extending part engaging with the edge and bottom of the rail foot flange, a vertically extending part having pivotal engagement with said transversely extending part below and with the rail above the foot flange and tie abutting means, substantially as described.

11. A rail anchor comprising a bottom engaging part, constructed to bear upon the bottom of a rail and a vertical pressure producing part adapted so to engage the bottom engaging part that said pressure producing part may be rotated transversely about a longitudinal axis below the rail when being forced into position and, when in position, move angularly about a transverse axis.

12. In a rail anchor, the combination with the rail, of a bottom engaging part constructed with a tie engaging portion and a vertical pressure producing part, constructed so to engage with said bottom engaging part below the rail that rotational movements of said pressure producing part about an axis below the rail will force surfaces of said pressure producing part into engagement with the upper surface of the base flange of the rail and thereby produce pressure of said bottom engaging part upon the bottom of the rail and that longitudinal movement of the bottom engaging part in relation to the rail will produce angular movement of said vertical pressure producing part about a transverse axis in said bottom engaging part and automatically increase the gripping action upon the rail.

13. A rail anchor, including, in combination with the rail, a part engaging the top

- and edge of the base flange at one side of the rail extending underneath and engaging the bottom of the base flange of the rail, and a dog, provided with means for engaging, rotatably, with said part below and with means for engaging with the rail above the base flange when said dog is moved angularly in relation to said part, substantially as described.
14. In a rail anchor, the combination with the rail, of a part engaging the bottom of the rail, a vertical pressure producing member, constructed to engage with said part below and to be forced into engagement with the rail above the base flange by rotation of said pressure producing member about an axis within said bottom engaging part, substantially as described.
15. In a rail anchor, the combination with the rail, of a clamp engaging with the base flange of the rail, a dog constructed to engage with said clamp and to be forced into engagement with the upper surface of the rail base flange by rotation about said clamp and tie abutting means, substantially as described.
16. A rail anchor, including, in combination with the rail, a rail base flange engaging part constructed with a tie abutting portion and a tension member constructed so to engage said base flange engaging part that transverse rotation of said member about said part will force said member into engagement with the upper surface of the rail base flange and draw said part into gripping engagement with the rail base flange and that longitudinal movement of the rail in relation to said part will produce angular movement of said member and automatically increase the grip of the device upon the rail.
17. In a device for preventing the creeping of rails, a rail base gripping and bottom engaging element transversely disposed in relation to the rail and a part so engaging the rail base and said element as to be rotatable in a plane transverse to the rail about an axis disposed below and between the two sides of the rail.
18. In a rail anchor, a rail base flange engaging and gripping element and a rail engaging device so engaging said element below the rail as to permit angular movements of said device about a longitudinal axis and about a transverse axis.
19. A device for preventing the creeping of rails, comprising a rail embracing and gripping part and a rail engaging pressure producing device so connected to said part as to be rotatable about an axis longitudinally disposed and an axis transversely disposed in relation to the rail.
20. In a rail anchor, a rail gripping member provided with a tie engaging portion and a rail engaging device so pivoted upon said gripping member below the rail as to be adapted to move angularly about two axes at right angles the one to the other for effecting the gripping action of said member.
- In testimony whereof, I have signed my name to this specification in the presence of two subscribing witnesses.
